UNITED STATES PATENT OFFICE.

ANDERS P. ANDERSEN, OF PROVIDENCE, RHODE ISLAND.

AUTOMOBILE RADIATOR.

1,425,933.

Specification of Letters Patent. Patented Aug. 15, 1922.

Application filed May 31, 1921. Serial No. 473,741.

To all whom it may concern:

Be it known that I, ANDERS P. ANDERSEN, a citizen of the United States, residing at Providence, in the county of Providence and State of Rhode Island, have invented new and useful Improvements in an Automobile Radiator, of which the following is a specification.

This invention relates to certain new and useful improvements in an automobile radiator and more especially to a radiator of the honeycomb type, the primary object being to provide a construction embodying simplicity in fabrication and possessing great cooling facilities.

An equally important object resides in the formation of the radiator units from a strip or sheet of material which is shaped and cut in a single operation and from which the several lengths for forming the units are severed, the length of each section varying according to the size of radiator to be constructed.

The invention further resides in the features of construction hereinafter described and claimed, reference being made to the accompanying drawing wherein—

Figure 1 is a fragmentary perspective view of a radiator water element constructed in accordance with the present invention;

Figure 2 is a similar view of the sheet from which the radiator is fabricated, viewing the sheet from the spacing end; and

Figure 3 is a perspective view of the sheet from the opposite end.

Referring more in detail to the accompanying drawing, the sheet 1 of light metal, preferably light brass, and of a suitable width and length, the latter being sufficient to produce several units, is passed through dies to cut and form the entire length into the configuration depicted in Figures 2 and 3, producing the corrugations with the raised solid webs 2 at one end and similar webs 3 at the opposite end. The webs 3 are slotted lengthwise of the sheet and, in the same die-cutting and shaping operation, the outer portions are shaped in the opposite direction to produce the spacing webs 4 which are reinforced by the strengthening ribs 5. Each of the webs constitutes one-half of a hexagon having a pair of vertical sides and pairs of upper and lower inclined sides or converging sides, the ribs 5 occurring in one of the inclined sides so as to leave

the vertical sides uninterrupted whereby they may have solid contact with the vertical sides of adjacent webs.

In assembling the sections into which the original sheet is divided, the adjacent sections are reversed to bring the spacing webs 4 of one section opposed to the webs 2 of the next adjacent section, thereby providing a spacing web at each side and the front and back of the zig-zag water course 6 as defined by two assembled sections. Thus, when two sections are in assembled relation, the web portions 7 will engage the web portions 8 and the web portions 9 will engage the web portions 10 thereby defining the vertical, zig-zag water passage 6. When two water courses are assembled the web portions 11 of the spacing webs will engage the web portions 10 outwardly of 75 and on the opposite side of the point of contact between the web portions 9 and 10. Thus, the solid web portion 10, while engaged only by a half-width web portion on one side in the make-up of a water course, is reinforced throughout the remainder of its width by the outwardly disposed, half-width web portion when the water courses are assembled.

With a suitable number of the sheets or sections assembled, they are held together in a form and dipped in solder to a depth sufficient to secure the parts firmly together. The depth to which the sections are dipped in solder is indicated at 12 in Figure 1.

The construction of the radiator is extremely simple since the original sheet may practically be of any length, in fact of such a length as to form all the elements of the radiator. The structure forms a very neat 95 honeycomb type and by reason of the spacing webs 4 large zig-zag air spaces or openings are formed so that the radiator has great cooling facilities.

Having thus described my invention, what I claim as new and desire to secure by Letters Patent is:—

1. A radiator comprising zig-zag water and air courses each water course defined by two nesting sheets of metal corrugated and having raised webs at each side to space the intermediate portions of the sheets, the web at one side only of each sheet and at relatively opposite sides being slotted at intervals lengthwise of the sheet and the outer portions of the slotted web being pressed in the opposite direction to form spacing webs

- for the adjacent water courses on both sides.
2. A radiator comprising a plurality of transversely corrugated sections of sheet metal offset along their edges to provide correspondingly shaped webs, each corrugation having a flat bottom and diverging sides, and portions of the web on one edge of each section being oppositely corrugated to provide a narrower, spacing web having 10 a flat side parallel with the bottoms of the section corrugations, said flat sides of the spacing ribs adapted for seating against the outer faces of the uninterrupted webs of an adjacent section.
- 15 3. In a radiator, a plurality of zig-zag water courses each defined by a pair of correspondingly shaped sections of sheet metal having offset webs uniting the pair of sections along their edges, portions of the webs 20 along the opposite edges of each course being struck out in an opposite direction only to form spacing webs for spacing adjacent courses at the front and rear edges of the water course.
- 25 4. A radiator comprising a plurality of zig-zag water courses, each formed of a pair of metal sheets having abutting offset edge webs at each side, portions of one web only of each sheet being correspondingly

30 stamped out in the opposite direction away from the water course to form a hexagon with the opposed portions of the web from which said first portions were formed, the stamped web of one sheet being on the opposite side of the water course and at the opposite edge thereof to the corresponding web of the companion sheet.

- 35 5. In a radiator, a length of sheet metal bent back and forth to form relatively offset, parallel portions joined by inclined sides 40 the edges of the length being offset to form webs and one of the webs being lengthwise slotted at intervals to divide the web into inner and outer series of web sections, one series being pressed in the reverse direction 45 to form portions parallel with the aforesaid parallel portions and joined to the other series of web sections by inclined sides certain of the latter being provided with strengthening ribs.

50 In testimony whereof I have signed my name to this specification in the presence of two subscribing witnesses.

ANDERS P. ANDERSEN.
